UNITED STATES PATENT OFFICE.

WILLIAM WHARTON, JR., AND EDWARD SAMUEL, OF PHILADELPHIA,
PENNSYLVANIA, ASSIGNORS TO WILLIAM WHARTON, JR., AND COMPANY,
INCORPORATED, OF SAME PLACE.

DESIGN FOR A RAILWAY-RAIL.

SPECIFICATION forming part of Design No. 18,327, dated May 15, 1888.

Application filed April 20, 1888. Serial No. 271,310. Term of patent 14 years.

To all whom it may concern:

Be it known that we, WILLIAM WHARTON, Jr., and EDWARD SAMUEL, both citizens of the United States, and residents of Philadelphia, Pennsylvania, have invented a new and original Design for a Railway-Rail, of which the following is a specification.

Our design for a railway-rail is fully illustrated in the accompanying drawing, the view 10 in which is a transverse section showing the outline of the rail.

The rail has a head, M, projecting laterally from one side of a depending web, N, and a flange, P, projecting laterally from the other 15 side of said web, the upper face *p* of the flange being in a different horizontal plane from the upper face *m* of the head. The head M has a straight under face, *n*, extending to its outer edge, *n'*. At the outer edge of the 20 flange P is a depending rib, *q*, between which and the depending web N a groove, *s*, is thus formed.

We claim—

The herein described design for a railway-rail having in transverse section the outline 25 illustrated, comprising the depending web N, the laterally-projecting head M, having a straight under face, *n*, extending to its outer edge, and the laterally-projecting flange P, having its upper face in a different horizontal 30 plane from that of the head, and having at its outer end a depending lip, *q*, between which and the web N is a groove, *s*, all substantially as shown and described.

In testimony whereof we have signed our 35 names to this specification in the presence of two subscribing witnesses.

WILLIAM WHARTON, JR.
EDWD. SAMUEL.
